[57] **CLAIM**

The ornamental design for a width maintaining cylinder and wheel assembly for use in textile machine, as shown and described.

DESCRIPTION

FIG. 1 is a perspective view of the width maintaining cylinder and wheel assembly for use in textile machine, showing my new design;

FIG. 2 is a top plan view thereof;

FIG. 3 is a bottom plan view thereof;

FIG. 4 is a side elevational view thereof;

FIG. 5 is the opposite side elevational view thereof;

FIG. 6 is an end elevational view thereof; and,

FIG. 7 is the opposite end elevational view thereof.

FIG. 1

FIG. 6

FIG. 7

FIG. 2

FIG. 3

FIG. 4

FIG. 5
